UNITED STATES PATENT OFFICE

ALFRED E. HUDD, OF BUCKINGHAMSHIRE, ENGLAND, ASSIGNOR TO RESERVE HOLDING COMPANY, OF KANSAS CITY, MISSOURI, A CORPORATION OF DELAWARE

TRACKWAY DEVICE

Original application filed October 12, 1928, Serial No. 312,025, and in Great Britain February 9, 1928.
Divided and this application filed February 17, 1930. Serial No. 428,957.

The present invention relates to trackway devices for use in train control systems and is more particularly concerned with the provision of a new type of magnetic device for operating apparatus on a locomotive adapted to be influenced by magnetic elements located along the track.

This application is a division of the copending application Serial No. 312,025, filed October 12, 1928, and contemplates a novel arrangement for neutralizing a permanent magnet which is specially applicable for train control purposes and consists of arranging the permanent magnets diagonally with respect to the track electromagnets which are also arranged diagonally with respect to the track in a symmetrical relation to the permanent magnets as regards the line parallel to the direction of running of the trains, the poles of each electro-magnet lying in the same plane at right angles to the track as the corresponding poles of the permanent magnet so that by energizing the electro-magnet in an appropriate way an armature in a magnetic circuit passing centrally over the magnetic system will be unaffected.

The features of the invention will be better understood by referring to the accompanying drawings, which illustrate one method of carrying the invention into effect as applied to systems employing the vacuum brake system of control although it will be understood that the invention is not limited to this type of system but is equally applicable to the compressed air system of control, and that various detail modifications could be made without departing from the spirit of the invention.

In the drawings, Fig. 1 illustrates a section of track showing the arrangement of the track elements and controlling circuits therefor. Figs. 2, 3, 4, and 5 illustrate the brake controlling apparatus on a locomotive and a cross section of the track, the track magnet for giving the partial brake application or "caution" signal being illustrated alongside the track magnet for giving a full brake application for the sake of convenience, although it will be understood that only one of these magnets normally would be seen in any cross section.

Referring now to Fig. 1, a section of the

trackway is shown with one rail 50 divided into blocks, the other rail 51 being continuous. A permanent magnet or inductor AI is shown at the entrance to one section, this permanent magnet being made up of a plurality of permanent magnets arranged in parallel with poles of one polarity connected to one magnetic member and poles of the other polarity connected to another magnetic member. At a short distance from the permanent magnet the first electro-magnet or inductor BI is shown, said electro-magnet being constructed of a number of electro-magnets in parallel arranged as in the drawing. These two magnets are located between the rails at the left-hand side of the track with respect to the normal direction of motion of the locomotive. The second electro-magnet or induction CI is arranged similarly but at the right-hand side of the track. This latter electro-magnet, which is effective only at "stop" or "danger" signals, is of peculiar construction in that a number of permanent magnets are arranged in the form of a series of V's with like poles adjacent to each other, while the same number of electro-magnets are similarly arranged and super-imposed on the permanent magnets in such a manner that when energized the polarities of the permanent magnets and the polarities of the electro-magnets are opposed to each other in a plane at right angles to the track so that the inductor CI has no effect on an armature on a passing locomotive, arranged in a magnetic circuit having poles lying laterally with respect to the track. When deenergized, however, the permanent magnets alone are effective to influence such an armature.

The permanent magnets can conveniently be bar magnets, as shown more clearly in Fig. 3 where PM represents one of the permanent magnets. The electro-magnet EM with its exciting coil EC passes underneath the permanent magnet PM, as shown, and is provided with pole pieces PP at the ends which extend upwards to the plane in which the permanent magnets lie. The magnets are conveniently enclosed in a container C of non-magnetic material, as shown.

The electro-magnets of the inductors BI

and CI are preferably energized only when a locomotive is passing. This is conveniently effected by providing a short insulated rail 49, between the sections of the rail 50, 5 which section is electrically bridged through the wheels and frame of a passing locomotive to complete the energizing circuit when the signal track relay or the like is conditioned at "clear". The respective inductors 10 B1 and C1, it should be understood, are so positioned with respect to rails 49 that the receivers AR and BR properly co-operate with B1 and C1 while the locomotive bridges across the insulation to complete the respective 15 circuits for B1 and C1.

Referring to Figs. 2, 3, 4, and 5, a brief description of the apparatus on a locomotive will now be given. It consists of two magnetic pick-up devices or receivers AR and 20 BR located side by side which are adapted to be influenced by magnetic impulses received from the inductors located along the track. Receiver AR is normally adapted to be operated when a locomotive is passing 25 track apparatus in a "clear" or "caution" condition, while the receiver BR is normally adapted to be operated when a locomotive is passing track apparatus in a "danger" condition; their respective functions, however, 30 may be completely reversed by the operation of the reversing valves RVa and RVb when the locomotive is running tender first. The construction of the receivers AR and BR is substantially identical, receiver BR being 35 complementary to receiver AR, so that when the locomotive is running tender first, receiver BR will operate in exactly the same relative manner as receiver AR and vice versa. The receiver AR is arranged to operate 40 each time the locomotive passes over an inductor A1, to initiate a brake application and to operate a whistle valve so that a warning indication is given to the engineer every time so that he will know that he 45 has passed over an "A" inductor such as A1. A partial brake application valve is also provided which tends to operate when the locomotive passes a deenergized "B" inductor such as B1, a full brake application valve 50 being provided to operate when passing a deenergized "C" inductor such as C1. An acknowledging lever AL is provided which when depressed neutralizes the effect of the partial brake application valve. A releasing 55 ejector valve REV of well-known type and two reversing valves RVa, RVb, are provided, the latter being operated by a single operation when the locomotive is running tender first.

60 Having briefly described the apparatus on the locomotive and along the track, a detailed description of the operation of the same will now be given.

In the first place, it will be assumed that 65 a distant signal is at "clear". Under this con-

dition the first electro-magnet or inductor B1 will be energized when a locomotive passes over the insulated rail 49 immediately preceding. This energizing circuit extends from one terminal of the battery associated with 70 the distant signal; through the switch, closed by said signal in "clear" position; the rail section 49, the frame of a vehicle of the train, to the upper rail of the track and through the windings of B1 to the other terminal of the 75 associated battery. The magnets of the track-way inductors are much more powerful than magnets 5, carried by the vehicle and, therefore, on passing over the inductor A1, the armature 2, which is polarized by the permanent magnet 5, of the receiver AR, will be 80 operated to its alternate position. The magnetic flux passing from the inductor A1 over the collector planes 1 and 1a will be such as to bring about this result. The magnet 5 will hold the armature in its alternate position after the inductor has been passed and until a stronger disturbing is received thereby. The polarized armature 2 in moving to its alternate position raises the valve 3 which 85 is held on its seat against atmospheric pressure by means of the spring 6, the chamber 4 being connected to the vacuum chamber through orifice 29. When valve 3 is lifted, therefore, chamber 4 is immediately raised 90 to atmospheric pressure as it is now connected to atmosphere through valve 3 by means of opening 61; chamber 4 leads through the reduced opening 59 to the chamber 60 behind diaphragm 8 of valve 7, so that atmospheric 95 pressure in this chamber will cause the diaphragm 8 to collapse, open valve 7, and admit atmospheric pressure through openings 30 to the pipe 9. Pipe 9 extends through the reversing valve RVa to pipe 10 and atmospheric pressure in space 14 behind the diaphragm 11 will now cause valve 12 to open 100 and air will be admitted to pipe 41 extending to the vacuum chamber, through the whistle 13 which will therefore sound. The size of 105 the ports of the valves 7 and 12 in comparison with the size of the port of valve 3 is such that atmospheric pressure will be almost instantaneously applied to the diaphragm 11 causing it to collapse, and consequently the 110 whistle will sound practically at the same instant as valve 3 is opened. Pipe 9 is connected to the vacuum chamber through a restricted orifice 13' so that a rapid opening 115 and closing of valve 3 will cause a comparatively long opening of the valve 12, thereby ensuring that a clear warning whistle is given at all speeds of the locomotive. On passing over the energized inductor B1 in which the 120 polarity of the electro-magnet is reversed with respect to the inductor A1 the polarized armature 2 is restored to its initial position, whereupon the valve 3 is closed. The closing 125 of valve 3 allows the vacuum to be restored in the pipes 9 and 10 and spaces 60 and 14 130

of valves 7 and 12, thereby closing said valves and effecting the stopping of the sounding of the whistle 13.

When the locomotive is passing a distant signal at "danger" the inductor B1 will be deenergized as no circuit is completed when the locomotive wheel bridges the short insulating rail 49 on account of the semaphore switch being open while the semaphore blade 10 is in danger position. On passing over the inductor A1 the polarized armature 2 will be moved to its alternate position and the valve 3 opened, and the whistle sounded as before. In this case, however, the inductor B1 is de-energized, wherefore the polarized armature 2 remains in its alternate position and the whistle continues to sound. The reservoir 15 is connected to the vacuum pipe 10 through the restricted orifice 16; hence, after a pre-determined time the vacuum in the reservoir 15 is reduced and atmospheric pressure is applied to the space 62 behind the diaphragm 17. This reduction of vacuum is gradual and is determined by the size of the reservoir 15 and the size of the restricted orifice 16. Usually a period of about 3 seconds would be allowed to elapse before there is sufficient pressure in space 62 to cause diaphragm 17 to collapse. It will therefore be seen that valve 18 does not open while valve 3 is opened when passing a signal at "clear" as the time that valve 3 is open is too short to allow the vacuum in chamber 15 to be sufficiently reduced. If, however, valve 3 remains open, then after approximately 3 seconds, valve 18 will open and admit atmosphere through orifice 31 to the train pipe 19, so that a partial brake application is made. The amount of reduction of vacuum in the train pipe is determined by the size of the orifice 31. As valves 3, 7, 12, and 18 are now continuously open to atmospheric pressure, the whistle will continue to sound and the brakes will continue to be applied until an acknowledgment of the existing condition is made and conditions are restored to normal. For this purpose an acknowledging lever AL (Fig. 5) is provided which will be operated by the engine-man, if alert, to open valve 20 and connect pipe 21 through the valve RVb to pipe 63 extending to the vacuum chamber. There will be, therefore, a sudden suction of air through the opening 22, and the pipe 21 to the vacuum chamber. This inrush of air is sufficient to pull the polarized armature 2 back to its initial position, thereby again causing the valve 3 to close and allowing valves 7, 12, and 18 to close; then the whistle will cease to sound and the partial application of the brakes will cease.

On passing a home signal at "clear" the electro-magnets of the inductor C1 will be energized over a circuit similar to that traced for inductor B1, and consequently as like poles of the inductor C1 are encountered at the same time by the two collector planes of

the receiver BR the armature of the receiver BR will not be affected.

If, now, the locomotive passes a home signal at "danger", the electro-magnets in the inductor C1 will be deenergized, because the circuit of the electro-magnets of C1 will be open at the semaphore switch, so that now the collector planes of the receiver BR will encounter poles of opposite polarity on the inductor of C1 due to the rear part of one collector plane being opposite one pole while the front part of the other collector plane is opposite a dissimilar pole and vice versa. The polarized armature 2a of the receiver BR will therefore be moved to its alternate position in a similar manner to the operation of armature 2 of the receiver AR, and will operate valve 3a which admits atmospheric pressure to the chamber behind the diaphragm of valve 7a. Valve 7a will, therefore, open and admit atmospheric pressure to the pipe 9a, which extends to the space 64 behind the diaphragm of the full brake application valve 23. Atmospheric pressure in this space 64 will cause diaphragm 38 to collapse, and valve 23 to open, whereupon atmospheric pressure is admitted to the train pipe 40, through orifices 39, to effect a full automatic brake application. This automatic brake application cannot be released until a certain time has elapsed after the engine-man has been operated by the engineer. The existing air-brakes handle is connected to the special releasing ejector valve REV. When the brake handle is moved to the "on" position, the reservoir RA is connected over pipe 25 to the vacuum chamber. The reservoir RA is, therefore, exhausted after a period determined by the size of the orifice 26 and the capacity of the said reservoir. This period may be varied from say 6 to 30 seconds. When the reservoir RA has its pressure sufficiently reduced the engine-man operates the releasing lever RL thereby opening the valve 37. In consequence, the reservoir RA is connected through releasing valve 37, reversing valve RVb, and pipe 27 to the opening 28. Hence, there will be a sudden rush of air through the opening 28 through the pipe 27, reversing valve RVb, releasing valve 37, to the reservoir RA. This rush of air is sufficient to pull the polarized armature 2a to its initial position, whereupon valve 3a is again closed and the automatic application of the brakes is released, control being now entirely in the hands of the engine-man. The opening 28 of the releasing pipe 27 is so proportioned that the polarized armature 2a cannot be pulled back to its initial position until the predetermined degree of vacuum has been produced in the reservoir RA. Also, the duration of the effective suction applied to armature 2a is limited to the capacity of the reservoir RA owing to the restriction of the opening 26; therefore, it is impossible to give

a prolonged pull at the suction outlet 28 to the armature 2a. The engine-man, therefore, after receiving a full automatic brake application, must, in order to effect the release of this application and to keep the locomotive under his own control, first put his brake valve handle to the "on" position and then depress the releasing lever of the valve 37 after the requisite time has elapsed.

10 When now a locomotive is running on the track tender first, the engine-man will operate the reversing valves RVa and RVb which are connected to the reversing gear on the locomotive. The operation of these valves, as will be readily seen from the drawings, completely reverses the pipe connections to the two receivers AR and BR and to the operating valves 12, 18 and 23, so that when the locomotive is running under these conditions the functioning of the control system will be exactly the same as has already been described for forward running with the difference that receiver BR takes the place of receiver AR in controlling the clear and caution conditions, while receiver AR now controls the danger conditions.

15 An arrangement is also provided whereby when a locomotive is required to back, for instance out of a station, against a "stop" signal, the inductor C1 at said signal is energized over a home insulating rail 52, independently of the signal, so that the inductor C1 does not influence the receiver BR to initiate a brake application, the locomotive being allowed to back under the control of the engine-man and independently of the home position wayside signals, the circuit extends over the rail section 52, the associated battery, the windings of C1, through the rail section adjacent 52 and through the frame of the locomotive back to rail section 52.

20 25 30 35 40 45 50

It will be appreciated that a control system has been devised which is very simple in construction and extremely rugged, being dependent for its operation entirely on pneumatic means, with the exception of the magnetic pick-up arrangements, and that to those skilled in the art many detail modifications could be made without exceeding the scope of the invention.

What is claimed is:

1. In a trackway device having utility in a train control system, a permanent magnet and an electro-magnet arranged in the form of an X, the said electro-magnet when energized being effective to render ineffective the field of said permanent magnet.
2. In a trackway device having utility in a train control system, a plurality of bar permanent and electro-magnets so arranged that the midpoints of the respective permanent and electro-magnets cross each other.
3. In a trackway device having utility in a train control or cab signal system, two magnets arranged in the form of an X; one

of said magnets being effective, upon energization, to render ineffective the field of the other.

4. In an electromagnetic structure having utility in a train control system, a plurality of electromagnets placed at right angles to each other each with one of its poles adjacent one of the poles of another, a plurality of permanent magnets placed at right angles to each other, said electromagnets and permanent magnets being also arranged at right angles to each other.

5. In a magnet structure, a plurality of magnets each of which has one or both its poles adjacent a pole of other of said magnets depending upon the position of the magnet in the structure.

6. In a magnet structure, a permanent magnet for operating a device brought within the field of said magnet, and an electromagnet so arranged with respect to said permanent magnet that the magnetic flux path of the electromagnet is at substantially right angles to the path covered by the flux transmitted by the permanent magnet, the energization of said electromagnet in the proper direction being effective to tend to operate said device in the reversed direction to that which the permanent magnet tends to operate said device, so that when the electromagnet is so energized the operation of the device by the permanent magnet is prevented.

In witness whereof, I hereunto subscribe my name this 22nd day of January, A. D. 1930.

ALFRED E. HUDD.
